UNITED STATES PATENT OFFICE

122,286

DESIGN FOR A TABLE TOP OR SIMILAR ARTICLE

Gorman L. Fisher, Binghamton, N. Y.

Application June 16, 1939, Serial No. 85,529

Term of patent 3½ years

To all whom it may concern:

Be it known that I, Gorman L. Fisher, a citizen of the United States, residing at Binghamton, in the county of Broome and State of New York, have invented and produced a new, original, and ornamental Design for a Table Top or Similar Article, of which the following is a specification, reference being had to the accompanying drawing, forming part thereof, and in which

I claim:

The ornamental design for a table top or similar article, substantially as shown.

GORMAN L. FISHER.
